UNITED STATES PATENT OFFICE.

BENSON JONES, OF MILL HAVEN, LOUISIANA.

DESIGN FOR AN ANGLE-PLATE.

SPECIFICATION forming part of Design No. 27,218, dated June 15, 1897.

Application filed February 3, 1897. Serial No. 621,895. Term of patent 7 years.

To all whom it may concern:

Be it known that I, BENSON JONES, a citizen of the United States, residing at Mill Haven, in the parish of Ouachita and State of Louisiana, have invented and produced a new and original Design for Railroad Angle-Plates, (fish-bars;) and I do declare the following to be a full, clear, and exact description of the same, reference being had to the accompanying drawings, forming a part hereof.

Figure 1 is a side elevation of my railroad angle-plate. Fig. 2 is a top plan view. Fig. 3 is an end view.

My design consists of an angle-plate having

a perforated body 1, flange 2, bulge 3, and 15 perforations 6 and 7, having depressions 11, and in the edges of flange 2 notches 12, 13, and 14.

Having described my invention, what I claim is—

The design for a railroad angle-plate, substantially as shown and described.

In testimony whereof I affix my signature in presence of two witnesses.

BENSON JONES.

Witnesses:

R. M. FILHISE,
T. C. McLAIN.
